UNITED STATES PATENT OFFICE.

THOMAS BARTON, OF EAST ORANGE, NEW JERSEY.

TIME AND DISTANCE RECORDING DEVICE.

1,404,683.

Specification of Letters Patent. Patented Jan. 24, 1922.

Application filed March 9, 1920. Serial No. 364,368.

To all whom it may concern:

Be it known that I, THOMAS BARTON, a citizen of the United States, residing at East Orange, in the county of Essex and the State of New Jersey, have invented a new and useful Improvement in Time and Distance Recording Devices, of which the following is a specification.

This invention relates to time and distance recording devices, particularly adaptable to auto trucks.

An object of this invention is to provide an improved device for feeding a recording tape in auto trucks and the like, whereby an accurate record may be kept of the time of stops and the distances traversed in a given period of time. A more specific object is to generally improve, simplify and condense the structure of such devices, and to provide a device which will be automatically operative when going in the desired direction and automatically inoperative when going in the opposite direction.

A further object of this invention is to provide an apparatus of this type whereby a greater number of miles may be recorded, not increasing the space required for the apparatus, and further to reduce the amount of record carrying material.

With these and other objects in view, the invention consists in the construction, combination, detail and arrangement of parts as hereinafter more fully described and claimed.

In the drawings:

Figure 1 is a front elevation of this device.

Figure 2 is a section at 2—2 in Figure 1.

Figure 3 is a section at 3—3 in Figure 2.

Figure 4 is a section at 4—4 in Figure 1.

Figure 5 is a detail showing member 4 of Figure 2 and parts co-operative therewith.

In the embodiment of my invention there is provided a shaft 2 suitably journaled and mounted in a housing 3, and adapted to interlock and be rotated by the usual flexible shaft from the automobile transmission. On the upper end of the shaft is mounted a dog 4, in the path of which is a radial projection from a shaft 5. Mounted on the lower end of the shaft 5 is a radial projection 6, in the form of a spear-head, upon which is mounted a pawl 7 held by a spring 8, yieldingly against a ratchet 9, so that when the dog 4 is rotated in one direction it engages the spear-head 6, causing the

pawl 7 mounted thereon to rotate the ratchet 9; but when rotated in the reverse direction, the dog 4 rotates the spear-head 6 in the reverse direction, but causes no movement of the ratchet 9.

Mounted also upon the shaft 5 in fixed relation thereto, is a worm 10 driving a worm gear 11. The worm gear 11 in turn actuates a gear 12 mounted on the same shaft, which co-meshes with a gear 13 actuating the same. This gear actuates a gear 14 mounted on the same shaft as gear 13; the gear 14 co-meshes with a gear 15, which actuates a gear 16 mounted on the same shaft. The gear 16 co-meshes with an idler gear 17, which comeshes with a gear 18, there being mounted on the shaft co-axial with the gear 18, a reel 19, which reel 19 is provided with a thumb nut 20 for releasing the same from a shaft 21 and is also held in predetermined position by a spring washer 22.

A tape 23 is provided to wind about a reel or spool 19, and passes through rollers 24 and 24' and passes over a stationary drum or frame 25 from a secondary spool 19'.

This tape is suitably divided and prepared, the mileage being recorded lengthwise and the time being recorded crosswise of the tape, eliminating waste or use of tape when the car or truck is not in actual operation. The tape is divided lengthwise in sections of one mile and crosswise to record in spaces of six hour or twelve hour division; in other words, the recorder or pencil will mark either six hours or twelve hours in travelling from one side of the tape to the other, and continues to record the following six hours or twelve hours when travelling in the opposite direction.

The mechanism for operating the record is as follows: The hand driving mechanism of the clock 26 is provided with a heart cam 27, mounted upon one of the shafts thereof, which heart cam gives an oscillatory motion to a lever 28, pivoted at 28^a, which lever 28 is connected by a link 28^b, pivoted at 28^c to a bell crank 28^d, which bell crank 28^d is pivoted at 28^e to a bracket 28^f, said link and lever being co-pivoted at 28^g. The link 28^b is provided with suitable play so that, upon the downward motion of the left-hand end of the lever 28, as shown in Figure 3, the bell crank 28^d will have a counter-clockwise motion upon its pivot 28^e. The bell crank 28^d is connected by a link 29 to a lever 29',

which lever 29' is connected by a pivot 29^b to a bifurcated bracket 29^a, the said link 29 and the said lever 29' being co-pivoted at 29^b. Thus, upon the counter-clockwise rotation of the bell crank 28^a the said link 29, which is pivoted thereto at 29^a will move to the left drawing the said lever 29' likewise to the left upon its pivot 29^b. Pivotally mounted at 29^c at the top of said lever 29' is a stylus retaining member 30 carrying a pencil 31, which, upon the movement of said lever 29' to the left, as shown in Figure 2, likewise moves to the left, causing the pencil to mark upon the tape 23. A spring 32 serves to push the pencil point against the surface of the tape by pressing upon the top of the mount 30.

It is quite obvious that when the machine is at rest there is no tape consumed, although a record is kept of the time during this rest; and it is also quite obvious from the structure set forth that a minimum amount of tape will be required to completely keep a record of the time of rest or the time of travel during a given period of travel.

Claims:

1. In an odometer, an annular housing, substantially diametrically opposed reels in the interior of said housing, means for rotating one of said reels by the driving mechanism of a vehicle, a tape, a guide for said tape substantially concentric to said housing, means for moving said tape over said guide, and means for marking said tape as said tape moves over said guide. 30

2. An odometer co-operating with a clock in recording time and distance comprising a casing normally adapted to form a shell for a clock and the mechanism of the odometer and clock arranged within the casing all substantially behind the normal face of the clock. 40

3. A clock provided with an annular housing, a tape, means for moving said tape, a guide for said tape in concentric relation to said housing, and mechanism for marking said tape by the operation of said clock, said mechanism beginning within said guide and extending to the exterior thereof. 45

THOMAS BARTON.
